UNITED STATES PATENT OFFICE.

JOHN C. WAHL, OF CHICAGO, ILLINOIS, ASSIGNOR TO THE WAHL COMPANY, OF CHICAGO, ILLINOIS, A CORPORATION OF DELAWARE.

MECHANICAL PENCIL.

Application filed July 17, 1925. Serial No. 44,191.

My invention relates to a pencil of the type in which the lead is moved longitudinally through the tip by mechanical means.

Among the objects of my invention is the provision of a mechanical pencil in which the lead may be propelled, repelled and expelled through the tip, and it contemplates novel means for effecting these results.

A further object of my invention is the provision of a pencil shorter in length than the usual mechanical pencil, and comprising such an arrangement of interior parts as to make possible the incorporation of a novel lead magazine without increasing the length of the pencil.

Another object of my invention is the provision of a novel form of lead magazine that may be used in either a long or short pencil, as desired, but is of especial value in a short pencil, in which it is vital to conserve longitudinal space.

A further object of my invention is a novel combination of the lead magazine and the lead propelling, repelling and expelling mechanism.

A further object of my invention is the provision of a more simple, economical and efficient pencil of the mechanical type.

Other objects, advantages and capabilities will hereinafter more fully appear.

My invention further resides in the combination, construction and arrangement of parts shown in the drawings, and while I have shown a preferred embodiment I wish it to be understood that the same is susceptible of modification and change without departing from the spirit of my invention.

In the drawings:—

Fig. 1 is a side view partly in elevation and partly in section of a pencil embodying my invention.

Fig. 2 is a longitudinal section of the upper portion of my improved pencil.

Fig. 3 is a longitudinal section of the remaining portion of the pencil extending from the line X—X at the bottom of Fig. 2 to the tip of the pencil.

Fig. 4 is a fragmentary longitudinal section of a portion of the pencil, showing the two cross-heads in their normally spaced apart positions which they occupy when there is a substantial amount of lead in the pencil.

Fig. 5 is a fragmentary longitudinal section of the lower portion of the pencil show-

ing the lower cross-head in engagement with the threads of smaller pitch, and the upper cross-head in lead expelling position.

Fig. 6 is a side elevation partly broken away of the inner tube, which carries the threads for imparting motion to the cross-heads, the upper left hand corner being shown in section for the sake of clearness.

Fig. 7 is a transverse cross-section taken on a plane through my pencil indicated on the line 7—7 of Fig. 4.

Fig. 8 is an end view looking down upon Fig. 6.

Fig. 9 is a detailed side elevation of the tube and associated parts for actuating the two cross-heads.

Fig. 10 is a detailed perspective view partly broken away of the member forming the lead magazine.

Fig. 11 is a perspective detail of the lead gripping and carrying tube.

Referring to the drawings my invention comprises an outer casing 1, at its lower end the tapered portion 2 terminating in the tip 3, which tip, as shown in Fig. 5, is formed with longitudinal opening 4 of a size to snugly permit longitudinal movement of the lead 5 therethrough. Fixed to the inside of casing 1 at a point adjacent the upper end of the tapered portion 2 is a transverse member 6, having a longitudinal bore 7, in which is secured the upper end 8 of the tube 9, the lower end of which tube is suitably and snugly fitted within the lower portion of the tapered end 2 of the pencil, with the bore of tube 9 and the bore in tip 3 in alignment. Fixed to the interior of casing 1 to rotate therewith is the tube 10 which, as shown in Fig. 5, engages at 11 with the transverse member 6.

Tube 10 is formed with interior threads 12 throughout the greater portion of its length, which threads 12 at their lower end merge into threads 13, which are of less pitch than threads 12, for a purpose to be hereinafter more fully set forth. Near its upper end the tube 10 is formed with an inwardly extending circumferential bead 14, and is also provided at diametrically opposite sides with longitudinal slits 15 to permit during assembly the entrance at this end of the tube of the tubular extension 16 of the actuating ring 17, with such a fit as to permit rotation of the actuating ring 17 with relation to the tube 10.

Fixed to rotate with the actuating ring 17 is the inner actuating tube 18 which, as shown in Fig. 9, is provided with diametrically opposite longitudinal slots 19, in which slots the edges of the cross-heads 20 and 21 are longitudinally slidable.

These cross-heads are provided on one or both edges, as desired, with threads 22 and 23, which are adapted to engage with the internal threads 12 and 13 of tube 10. These threads 22 and 23 of cross-heads 20 and 21 are of such size and arrangement that they will operatively engage either of threads 12 or 13, which is especially true of the lower cross-head 21, which at the lower end of its movement moves into full engagement with threads 13, as shown in Fig. 5, which is the lead expelling position of the cross-heads.

As seen in Fig. 2, the lower cross-head 21 is provided with a longitudinal bore, in an enlarged portion of which is secured the upper end of the lead gripping and carrying tube 24 which, when the cross-heads are in their uppermost position, as shown in Fig. 1, enters a short distance into tube 9. Fixed in the upper cross-head 20 is a plunger rod 25, which extends, as shown in Fig. 3, nearly to the lower end of lead gripping tube 24, when the cross-heads are in their uppermost position. This leaves a portion 26 (see Fig. 3) of the lead gripping tube available at the lower end of the plunger rod 25 for gripping and securely holding the upper end of the lead, which is facilitated by the resilient nature of the material of tube 24, and the provision of a longitudinal slit 27 lengthwise of this tube, which tube is normally slightly less in diameter than the diameter of the lead.

The actuating ring 17 has an upwardly extending tubular portion 28, upon which is screw-threaded the sleeve 29, carrying the eraser 30 and the eraser securing member 31, the bottom of which latter member also forms a closure for the lead magazine about to be described.

The general construction of the main operating parts of this pencil is substantially the same as those described and claimed in my co-pending application, Serial No. 44,190, filed July 17, 1925. The present pencil, however, being much shorter in length than that shown and described in my said co-pending application, necessitates an entirely different form of magazine for the extra leads.

The main construction of this magazine is shown in perspective in Fig. 10, and comprises parts preferably stamped from a single piece of metal, although I wish it understood that the same might differ somewhat from this exact construction, without departing from the spirit of my invention.

The form of magazine chosen for illustrative

purposes in this application comprises the two downwardly depending legs 32 and 33, which are joined together at their upper end by the plate member 34, having the projecting ends 35 and 36. The marginal edges of legs 32 and 33 are angularly bent to form the side portions 37, 38, 39 and 40, respectively, which side portions form the sides of the two lead magazines positioned one upon each side of the cross-heads. The lower ends of legs 32 and 33 are bent outwardly at right angles to form the end portions 41 and 42, respectively, whose functions are to form the bottom of the lead magazine.

It will be noted that the edges 35 and 36 of the plate 34 are arcuately shaped so as snugly to fit the inner peripheral wall of the tube 18. Likewise the edges of the end portions 41 and 42 are arcuately shaped to fit the inner wall of the tube 18. By reference to Figure 10, it will be seen that the two legs 32 and 33 are substantially resilient due to their connection at the plate 34 and hence when this unit is inserted within the tube 18 the legs 32 and 33 will tend to spread so that the end portions 41 and 42 will frictionally grip the inner walls of the tube 18 and hold the magazine member firmly in position. If desired the member may be soldered or otherwise retained in such position but the construction shown and described is simple, economical and effective.

In assembling these parts the legs 32, 33, of cross-bar 34, and their associated parts, are inserted into the actuating tube 18, with the cross-heads 20 and 21 occupying a position between legs 32 and 33, the edges of which cross-heads, as stated above, also extend through slots 19 for engagement with the threads in tube 10. The extending ends 35 and 36 of cross-bar 34 prevent the inadvertent dropping of an extra lead into that portion occupied by the cross-heads. These lead magazines are made available by unscrewing sleeve 29 from the threaded extension of actuating ring 17, thus giving ready and easy access to the extra leads. By positioning the cross-heads between legs 32, 33, of the lead magazine the length of the pencil is very materially decreased.

The operation of my pencil is as follows:

The operator by grasping the casing 1 in one hand and rotating the actuating ring 17 with the other causes a rotation of the two cross-heads 20 and 21, it being assumed that in starting this operation the cross-heads stand in their uppermost position, as shown in Figs. 1, 4 and 9. This rotation causes the crossheads, which in this position engage threads 12, to move longitudinally of the casing simultaneously and at the same speed until the lower cross-head 21 comes into engagement with the threads 13 of less pitch, which immediately decreases the speed at which the lower cross-head 21 moves longitudi-

- dinally, thus permitting the upper cross-head 20 to catch up with the lower cross-head, which movement causes the plunger rod 25 to move longitudinally through gripping tube 24 into the position shown in Fig. 5, which will completely expel the remaining fragment of lead from the tip. During the movement of the cross-heads prior to engagement of the lower cross-head with threads 13 the plunger rod 25 and lead gripping tube 24 will move together to either propel the lead through the tip or repel the same, depending upon the direction of rotation of the cross-heads.
- 15 It will thus be seen that I have provided a propel, repel, expel pencil that can be constructed of small length, and have incorporated in the same a novel and readily available magazine for extra leads.
- 20 I claim:—
1. In a mechanical pencil, a casing, an actuating tube, an actuating member longitudinally movable in said tube, and a pair of elongated members insertible into said tube to straddle said actuating member and having sides and bottoms cooperating with said tube to define a lead magazine.
  2. In a mechanical pencil, a casing, an elongated hollow actuating element rotatable in said casing, and a magazine member insertible into said hollow element, said member having a pair of depending legs, each of the legs having sides and a bottom contacting at their outer edges with the inner walls of the hollow element to form a pair of spaced magazines for extra leads.
  3. In a mechanical pencil, a tubular member, and means forming a lead magazine comprising a pair of spaced apart legs, each of said legs having outwardly extending sides and an angular bottom, and a top member uniting said legs to permit them to be simultaneously inserted into the interior of a pencil to cooperate with said member to define compartments for extra leads.
  4. In a mechanical pencil, a casing having internal threads, a slotted actuating tube rotatable in the casing, a magazine element insertible into the tube and having a pair of depending legs each of which is provided with sides and a bottom bent outwardly to contact with the inner surface of the tube to form a pair of spaced lead magazines, and a cross-head the edge of which extends through the slot of the tube into threaded engagement with said internal threads, said crosshead having longitudinal movement between said legs upon rotation of the actuating tube with relation to the casing.
  5. In a mechanical pencil, a casing having internal threads, a slotted actuating tube rotatable in the casing, a magazine member insertible into the tube and having a pair of depending legs each of which is provided with sides and a bottom bent outwardly to contact with the inner surface of the tube to form a pair of spaced lead magazines, and a cross-head the edge of which extends through the slot of the tube into threaded engagement with said internal threads, said crosshead having longitudinal movement between said legs upon rotation of the actuating tube with relation to the casing.
  6. A magazine member for mechanical pencils, said member being made from a single flat piece of metal and formed to have a flat central portion with extending ends, and a pair of depending legs, each of said legs being bent at right angles to the central portion and formed with outwardly bent sides and a bottom portion extending outwardly at substantially right angles to its respective leg.
  7. In a mechanical pencil a casing, lead propelling mechanism in said casing having an actuating tube, means forming a lead magazine in said tube comprising a pair of downwardly depending spaced apart legs, each of said legs having outwardly extending sides and an outwardly extending bottom substantially engaging the inner surface of the tube.
  8. In a mechanical pencil, an actuating tube, means forming a magazine for extra leads in said tube comprising a pair of spaced apart legs connected at their upper ends and extending downwardly therefrom in said tube and having bent sides and bottoms engaging the inner surface of the tube, and propelling elements longitudinally movable between said legs.
  9. In a mechanical pencil, an actuating tube, means forming a magazine for extra leads in said tube comprising a pair of spaced apart legs longitudinally disposed in said tube and having bent sides and bottoms engaging the inner surface of the tube, propelling elements longitudinally movable between said legs, and a removable cover for said magazine.
  10. In a mechanical pencil, a tubular element, a magazine member having spaced apart legs adapted to cooperate with said element to define two lead chambers, and means for connecting said legs at their upper ends and adapted as an end closure for the space between said legs.
  11. In a mechanical pencil, a casing having threads, a rotating actuating tube therein and means forming a lead magazine comprising a sheet metal member disposed within the actuating tube and bent to provide spaced resilient legs having portions adapted frictionally to engage the inner walls of the tube and form a lead chamber therewith and detachably to hold the lead magazine forming means in position within the actuating tube and an actuator disposed within the

magazine forming means and the actuating member and adapted to engage the threads of the casing.

12. In a mechanical pencil, a casing having internal threads, an open-ended, slotted actuating tube therein, a lead feed member having a cross-head projecting through the slot of said tube to engage the threads, a member insertable through the open end of the slotted tube and having spaced apart legs receiving the cross-head therebetween, said legs having portions cooperating with the inner walls of the tube to form a lead magazine open at the rear end of the pencil

and a cap adapted to close the rear end of 15 said magazine.

13. In a mechanical pencil, a threaded casing, an actuating tube within the casing, a member within the actuating tube and having parts cooperating with the actuating 20 tube to define a lead magazine, and a lead feeding member disposed within the first mentioned member and projecting through the walls of the actuating tube to engage the threads of the casing. 25

In witness whereof, I hereunto subscribe my name to this specification.

JOHN C. WAHL.
